UNITED STATES PATENT OFFICE.

JOSEPH W. JONES, OF NEW YORK, N. Y., ASSIGNOR TO LOVELL-McCONNELL MANUFACTURING COMPANY, OF NEWARK, NEW JERSEY, A CORPORATION OF NEW JERSEY.

DESIGN FOR A HORN.

41,563.

Specification for Design.

Patented July 11, 1911.

Application filed July 8, 1909. Serial No. 506,639. Term of patent $3\frac{1}{2}$ years.

To all whom it may concern:

Be it known that I, JOSEPH W. JONES, a citizen of the United States, and a resident of the city, county, and State of New York, (whose post-office address is Broadway, at Seventy-sixth street, New York city, New York,) have invented a new, original, and ornamental Design for Horns Particularly Adapted for Use upon Automobiles, which design is fully set forth in this specification,

reference being had to the annexed drawing, forming part hereof, which is a side view of a horn embodying my invention.

I claim:

The ornamental design for a horn, as shown.

JOSEPH W. JONES.

Witnesses:

W. L. BEARDSLEY,
THOS. S. BARRETT.
